UNITED STATES PATENT OFFICE.

CHARLES E. SCRIBNER, OF JERICHO, VERMONT, ASSIGNOR TO WESTERN ELECTRIC COMPANY, OF CHICAGO, ILLINOIS, A CORPORATION OF ILLINOIS.

ELECTRIC POLE-CHANGER.

SPECIFICATION forming part of Letters Patent No. 760,574, dated May 24, 1904.

Application filed September 15, 1902. Serial No. 123,403. (No model.)

To all whom it may concern:

Be it known that I, CHARLES E. SCRIBNER, a citizen of the United States, residing at Jericho, in the county of Chittenden and State of 5 Vermont, have invented a certain new and useful Improvement in Electric Pole-Changers, of which the following is a full, clear, concise, and exact description.

My invention relates to pole-changers and 10 their circuits; and its primary object is to obtain an efficient ringing-current at small expense.

The invention is especially applicable for 15 use in moderate-size telephone-exchanges in which the transmitter-battery is provided at the different stations in contradistinction to those systems in which said battery-supply is centralized. My improvements are such, however, that their introduction, I believe, 20 may result in the extension of the use of pole-changers into quite large exchanges.

My invention contemplates the use of a pole-changer in connection with a signaling-battery, the battery having one pole thereof connected, through a condenser or resistance, to 25 the vibrating or oscillating contact-arm, other branches from said pole being connected to the other and alternate contacts of the pole-changer in such a manner that when 30 current is sent to line the resistance will be included in the circuit at the time the other contacts or alternate connections are broken, thus preventing sparks which would otherwise result from the extra current due to self-induction in such circuits. It is, moreover, of 35 advantage to thus smooth the signaling-current of telephone-lines, since its inductive effect upon adjacent lines is minimized thereby.

My invention will be more readily understood by reference to the accompanying drawings, in which—

Figure 1 is a plan view of the pole-changer with an ordinary electromagnet and circuit-breaker included in a battery-circuit for 40 vibrating the pole-changer arm. Fig. 2 is an elevation of the pole-changer as seen from line 2 2 of Fig. 1 and showing the vibrating arm in its intermediate or open-circuit position. Fig. 3 is a view of the same, showing

the contact-arm moved to its extreme right 50 position. Fig. 4 shows the same in the position which it assumes when the vibrating arm moving to the left, as indicated by the arrow, has parted from the spring to the right and is just closing upon the spring to the left. 55 Fig. 5 is a view of the same upon line 5 5 of Fig. 3. Fig. 6 is a diagram illustrative of the pole-changer as used in a telephone system for directing the signaling-battery over the line, and Fig. 7 is a modification or alternate arrangement which consists in substituting a condenser for the resistance.

Like parts are indicated by similar characters of reference throughout the different figures.

The pole-changer proper, as shown in Figs. 1 to 5, consists of the vibrating contact arm or lever *a*, the pair of contact-springs *b c* on one side of said arm, and the corresponding pair of contact-springs *d e* on the other side 70 of said arm, with the contact *f* interposed between springs *b d*, upon which said springs *b d* are alternately closed, and the insulating stud *g*, pivotally or movably mounted between said springs, which stud when pressed upon by one of said springs is forced against the other to move the same.

In Fig. 6 the telephone-line is shown provided with two stations A B, at each of which is provided the usual bell, generator, telephone, transmitter, induction-coil, and switch. The line extends in two branches 1 2 to the central office, where are provided the usual line-annunciator *h* and spring-jack switch *k*. The operator is provided with plugs and calling keys, as indicated at *l m n*. The pole-changer is connected with the battery *o*, as shown, the resistance *p* of, say, five thousand ohms being included in the branch from the pole of the battery which connects with the arm *a*. The 90 same pole of the battery, as shown by wire 3, is branched to the contacts *c e* of the pole-changer. The other pole of the battery—in this instance the negative pole—is connected by wire 4 with the binding-post which supports the contact *f*, which contact *f* is interposed between the springs *b d*. The stud *g* I have already described as serving as a medium

by which pressure of either one of the springs *b d* may be transferred to the other to move the same.

In Fig. 7 I have shown a battery *o* connected 5 with the pole-changer, as in Fig. 6, a condenser *q* of, say, two microfarads being used in place of the resistance *p* of said Fig. 6.

Assume that the operator at the central office desires to signal the subscriber A. She will 10 insert plug *l* in spring-jack *k* and by means of signal-key *m* connect the battery *o*, through the pole-changer, with limb 1 of the telephone-line, which limb leads through the bell at said station A to ground. The current transmitted 15 will be sent in alternations. The arm *a*, it will be assumed, is started when the key *m* is operated. Assume that said arm is vibrated, as illustrated in Fig. 1, by an electromagnet or any other suitable means, and we will follow 20 the movements of said arm to the right and to the left in its vibrations. The arm will first close on contact *b* and moving on carry said arm *b* into contact with the left and outer spring *c*. This position is illustrated in Fig. 25 3, at which time it will be observed that the positive pole of the battery is connected directly by wire 3 to spring *c*, and hence to spring *b*, and also at the same time there is a connection from the same pole of the battery 30 through a condenser or resistance to arm *a* and from the right contact of said arm *a* to said spring *b*—that is to say, the condenser or resistance is in a shunt of the circuit connection through wire 3. The arm having completed 35 its excursion to the right returns toward the left. First spring *b* moves away from spring *c*, and coming against the stud *g* spring *d* is started in its movement toward the left, being separated from contact *f*, and then 40 spring *b* comes against said contact *f*, as shown in Fig. 4, and the arm *a*, continuing its stroke, carries spring *d* into contact with the outer left spring *e*. The arm returning to the right again will permit spring *d* by its own tension 45 to separate from spring *e*. At the moment the circuit is broken by the separation of springs *d e* or by the separation of springs *b c* it should be observed that there is a shunt around the said contact-springs through 50 resistance, which may be in the form of a usual resistance-coil of, say, five thousand ohms, or through a condenser of, say, two microfarads, so that there will be no spark or burning at the contacts that are thus shunted.

When one of the keys—as, for example, key *m*—is operated, the current sent over one of the limbs of the circuit—in this instance limb 1—will in the first instance—that is, when contact *a* touches spring *b*—pass through the resistance or condenser *p* or *q*, and immediately thereafter as the spring *b* touches spring *c* the final impulse of the battery will be thrown on the circuit. Now when the oscillating or moving contact-arm *a* changes its direction of motion, permitting springs *b c* to separate, the

break between the contacts *b c* will be bridged or shunted by the resistance or condenser, so there will be no harmful spark developed due to the self-induction of the circuit 1, which includes the signal-bell or annunciator at station A. The same is true as to the operation of springs *d* and *e*. 70

I am thus enabled to provide an alternating current for operating signal-bells and annunciators by the use of battery-current and 75 at the same time avoid sparking at the pole-changer as the contacts are alternated, the tendency to such sparking being especially pronounced by reason of the fact that in such circuits the signal-receiving device is necessarily of considerable inductance. 80

From the foregoing description it appears that in my pole-changer the break made on the separation of contacts *b c* and *d e* will be bridged only at the very moment of their 85 separation, which is the instant at which spark would be liable to be developed. Thus the resistance or condenser is included in the battery-circuit only at the precise instant or instances when needed to perform its function of preventing sparking and at other times is disconnected, so that there is no wasteful flow of current through the same. 90

Having thus described my invention, I claim as new, and desire to secure by Letters Patent, 95 the following:

1. The combination with a circuit containing a signal-receiving device of considerable inductance, of a battery and a pole-changer operating to convert the direct current from the battery into alternating current to actuate the signal-receiving device, said pole-changer comprising switch-springs for connecting the two poles of the battery alternately with the two sides of the signal-circuit, a contact-lever and means for oscillating the same to operate said switch-springs, and a circuit including a spark-preventing device controlled by said contact-lever and momentarily connected in shunt about the switch-springs when the same are operated to break circuit, whereby alternating current from the battery is directed over the circuit to operate the signal-receiving device while sparking is prevented. 100 110 115

2. The combination with an electromagnetic signal device adapted to be operated by impulses of current, of a circuit therefor including a source of constant direct current, a switch operating to intermittently make and break the said circuit, whereby impulses of current are produced to actuate said signal device, a conductor adapted to shunt said switch, a spark-preventing device included therein, and a key controlling said shunt-conductor and co-operating with the switch to close the shunt momentarily while the switch operates to break circuit, whereby the spark at break is suppressed. 120 125 130

3. The combination with an electromagnetic signal device adapted to be operated by alter- 130

nating current, of an actuating-circuit therefor, extending to two switch-terminals of a pole-changer, a source of direct current, other switch-terminals of said pole-changer connect-
5 ed to the two poles of said source of current, means operating to bring the first-mentioned switch-terminals alternately into connection with the two poles of the source of current at the switch-terminals thereof, to cause cur-
10 rent impulses of alternating direction to flow through the signal device, a local circuit of the pole-changer including a condenser, and a switch operated by the aforesaid means to mo-

mentarily complete said local circuit during the break in the shunt of that portion of the ac-
15 tuating-circuit first broken at the switch-terminals of the pole-changer, whereby the spark at break caused by inductance in the circuit is suppressed.

In witness whereof I hereunto subscribe my 20 name this 23d day of July, A. D. 1902.

CHARLES E. SCRIBNER.
